UNITED STATES PATENT OFFICE.

ISAAC SHERMAN SLADE, OF SAN FRANCISCO, CALIFORNIA, ASSIGNOR TO SLADE MANUFACTURING COMPANY, OF SAN FRANCISCO, CALIFORNIA, A CORPORATION OF CALIFORNIA.

CONDIMENT-HOLDER.

1,227,331.

Specification of Letters Patent.

Patented May 22, 1917.

Application filed September 26, 1914. Serial No. 863,686.

To all whom it may concern:

Be it known that I, ISAAC SHERMAN SLADE, a citizen of the United States, residing at San Francisco, in the county of San Francisco and State of California, have invented certain new and useful Improvements in Condiment-Holders; and I do hereby declare the following to be a full, clear, and exact description of the invention, such as will enable others skilled in the art to which it appertains to make and use the same.

This invention relates to condiment holders, and the primary object of the invention is the provision of an attachment for condiment holders of the usual construction, which attachment will prevent the clogging of the working openings of the holders.

Another object of this invention is the provision of a shaker top or attachment as above specified which has associated therewith a closure for the egressing openings, which will prevent to a material extent the ingress of moisture into the condiment holders and thereby prevent the fusing of the condiment retained in the holders which impairs the egressing of the same from the condiment holder.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters of reference designate like or corresponding parts throughout the several views, and in

40 which:—

Figure 1 is a central sectional view through the improved shaker top for a condiment holder.

Fig. 2 is a cross sectional view on the line 45 2—2 of Fig. 1.

Fig. 3 is a top plan view of the shaker top for the condiment holder, the closure for the egressing openings being removed therefrom.

50 Fig. 4 is a bottom plan view of the closure for the egressing openings of the condiment holder shaker top.

Referring more particularly to the drawings, 1 designates the shaker top for a condiment holder, which is internally screw

threaded at the lower end thereof, but it is to be understood that the shaker top may be externally screw threaded if it is necessary for the attaching of the same to various types of condiment holders, this feature forming no part of the invention.

The shaker top 1 is constructed of a shell of sheet metal as is ordinary in the construction of devices of this character and it has its upper end or top recessed, and having the top proper spaced or horizontal and provided with a plurality of radially disposed openings 3, which openings are provided for the egressing of the condiment from the condiment holder (not shown) to which the shaker top 1 is attached. The top 2 of the cover or shaker top 1 is connected to the sides of the shaker top 1 by inclined connections 4, which form beveled edges against which the beveled edge 5 of the cover or closure 6 rests. The beveled edge 5 of the cover or closure 6 extends entirely about the circumference of the cover and fits snugly within the recess formed by the indentation of the top 1, as is clearly shown in Fig. 1 of the drawings. The cover or closure 6 has a plurality of depending lugs 7 formed thereupon, which lugs are spaced for insertion into the openings 3 formed in the top 2.

The top 2 of the shaker top 1 has a rectangular tube 10 extending downwardly therein and disposed centrally within the shaker top 1. The tube 10 is supported within the shaker top 1 by transversely extending radiating bracing wires 11, which wires are secured to the sides of the shaker top 1 and the tube 10 in any suitable manner.

The cover 2 has a stem 12 formed thereupon, and depending therefrom, which stem is slidably seated within the sleeve 10. The stem 12 is provided with a longitudinally extending transversely disposed slot 13, which receives the cross pin 14, which cross pin is carried by the sleeve 10 and rides within the slot 13 for limiting the upward movement of the cover 6 with respect to independent movement of the shaker top 1.

In the operation of the improved shaker top for condiment holders, as heretofore described; when the condiment holder (not shown) to which the shaker top 1 is attached, is inverted for shaking condiment

- therefrom, the cover 6 moves away from the top 2 and permits the condiment to pass outwardly through the openings 3. Immediately upon the proper repositioning or straightening up of the condiment holder the cover 6 will move downwardly and the lugs 7 will be disposed within the openings 3, preventing the openings from becoming clogged by the condiment and also owing to the fact that the cover fits snugly and firmly within the recess formed by the indenting of the shaker top 1, the passage of moisture into the condiment holder will be materially decreased.
- 15 The stem 12 and the sleeve 10 guide the movement of the cover 6 while the cross pin 14 sliding in the slot 13 limits the outward independent movement of the cover with respect to the condiment holder.
- 20 The openings 3 which are formed in the top 2 of the shaker top 1, are substantially frusto-conical shaped, having their inner ends of greater diameter than the outer ends, which communicate with the outer surface of the top 2 and permit of the passage of the condiment therefrom. This feature also facilitates the elimination of the clogging of the openings by the condiment.
- In reducing the invention to practice certain minor features of construction, combination and arrangement of parts may necessitate alterations to which the patentee is entitled provided such alterations are com-

prehended within the scope of what is claimed.

What is claimed is:—

The combination with a condiment holder, of a stopper therefor, said stopper including a cylindrical shell having a perforated top, which top is recessed, said recess having a plane bottom wall and upwardly and outwardly inclined side walls, a closure provided with a plane inner face and upwardly and outwardly inclined side walls, lugs secured to and depending from the under side of said plane inner face and having a length greater than the depth of said perforations in said top, and means adapted to permit said closure to move in a vertical plane into and out of said recess by the inverting of the condiment holder, said lugs adapted to clear said perforations of the contents of the condiment holder when the closure moves into said recess, said inclined edges of the closure having frictional engagement with the inclined side walls of the recess when in a closed position thus preventing the contents of the condiment holder from becoming wet or the entering of foreign matter therein.

In testimony whereof I affix my signature in presence of two witnesses.

ISAAC SHERMAN SLADE.
